UNITED STATES PATENT OFFICE.

JOHN H. KING AND JOHN L. MILLS, OF LIBERTY CENTRE, INDIANA.

CHURN.

SPECIFICATION forming part of Letters Patent No. 350,933, dated October 19, 1886.

Application filed July 22, 1886. Serial No. 208,768. (No model.)

To all whom it may concern.

Be it known that we, JOHN H. KING and JOHN L. MILLS, citizens of the United States, residing at Liberty Centre, in the county of 5 Wells and State of Indiana, have invented a new and useful Improvement in Churns, of which the following is a specification.

This invention relates to that class of churns in which the dasher reciprocates vertically, and the object of the invention is to produce a churn of this class which shall more thoroughly break up and gather the butter than has heretofore been possible.

To the above purpose the invention consists 15 in certain peculiar and novel features of construction and arrangement, as hereinafter described and claimed.

In order that our invention may be fully understood, we will proceed to describe it with 20 reference to the accompanying drawings, in which—

Figure 1 is a front elevation of our improved churn; and Fig. 2 is a perspective view of the same, the churn-body being removed.

25 In the said drawings, A designates the churn-body, which may be of the usual or any preferred form applicable to a vertically-reciprocating dasher.

The cover of this churn is formed of two 30 independent sections, a a'. The section a is simply set into the top of the body A and held thereon by a hook, a², attached to the churn-body, which engages an eye, a³, attached to the said section. The section a' is 35 permanently attached to the churn-body by hinges a⁴, and is also provided with eyes a⁵, which are engaged by hooks a⁶, attached to the churn-body.

Upon the section a' is secured the standard 40 or frame B, which supports the mechanism for actuating the dasher. This frame consists of the two legs b, connected together at their upper ends by a solid plate, b', and also a vertical guide-piece, b², lying between said 45 legs b.

C designates a gear-wheel, which is journaled upon a stub-shaft, c, formed on the front side of plate b'. This gear-wheel is provided with an operating-handle, c', and the

teeth c² of said wheel extend inwardly from 50 the inner side of its rim, as shown.

D designates a gear-pinion, which is journaled upon the rear side of plate b', and the teeth d of which mesh with the teeth c² of wheel C. Upon its rear side this pinion carries an arm, d', having a groove, d², for a purpose hereinafter described. 55

Upon the rear side of plate b' is formed a bracket, E, which is provided with an annular socket, e, through which passes loosely 60 a tube, F, as shown, to which the dasher-rod G is attached by means of a set-screw, f. The tube or sleeve F is formed with a spiral slot, f', into which extends a pin, e', inserted 65 through the socket e.

To the lower end of the sleeve or tube F is pivoted the lower end of an arm, H, the upper end of which is pivoted to a bolt, h, which slides in the groove d² of the arm d', before mentioned, whereby the stroke of the dasher-rod is varied at will. The lower pivoted end of arm H is connected to a block, h', which 70 slides upon the guide-piece b², before referred to.

To the lower end of the dasher-rod G are 75 attached radial dashers g, g', and g'', which are located in different horizontal planes and are inclined, as shown, so as to operate obliquely upon the cream.

From the foregoing description it will be 80 readily understood that when the wheel C is turned the dasher-rod will be reciprocated vertically and simultaneously oscillated in a circular direction at great speed, which, with the particular arrangement of dashers above 85 described, will quickly and thoroughly break up and gather the butter. It will also be seen that the dasher-rod may be raised and lowered in its sleeve, so as to accord with various quantities of cream, and that the length 90 of stroke of the dasher-rod may be readily varied. The arrangement of the covers permits the ready inspection and cleaning of the churn, as well as the convenient removal of its working parts. 95

Having thus described our invention, we claim—

The combination, with the churn-body and

its cover, of the frame B, having plate b' , guide-piece b^2 , and bracket E, with socket e , of the gear-wheel C, gear-pinion D, having grooved arms d' , the tube F, having the spiral slot, the arm H, and the dasher-rod G, attached to the tube F, substantially as specified.

In testimony that we claim the foregoing as

our own we have hereto affixed our signatures in presence of two witnesses.

JOHN H. KING.
JOHN L. MILLS.
